UNITED STATES PATENT OFFICE.

SELDEN A. DAY, OF BOWLING GREEN, OHIO, ASSIGNOR TO THE DAY
PROJECTILE COMPANY, OF NEW YORK, N. Y.

LUBRICATING-PROJECTILE.

SPECIFICATION forming part of Letters Patent No. 407,890, dated July 30, 1889.

Application filed March 6, 1889. Serial No. 302,175. (No model.)

To all whom it may concern:

Be it known that I, SELDEN A. DAY, a citizen of the United States, residing in Bowling Green, county of Wood, and State of Ohio, 5 have invented certain new and useful Improvements in Projectiles, of which the following is a specification.

This invention relates to projectiles for fire-arms, including either small-arms or ordi- 10 nance, the invention being applicable to bullets, solid shot, and explosive shells.

My improved projectile is designed especially for use in fire-arms the bore of which is rifled in order to impart a rotary motion to 15 the projectile during the act of firing.

The objects of my invention are to impart an accelerating rotary motion to the projectile, thereby overcoming its inertia gradually and accomplishing the purpose of an "in- 20 creasing-twist" rifling without incurring its disadvantages, and to provide for the more thorough and effective lubrication of the bore than has heretofore been accomplished.

To this end my improved projectile is con- 25 structed with a body portion of any suitable proportions and with a separate base or sabot connected to it through the medium of a screw-thread and normally partly unscrewed. The body of the projectile is formed of a mass, 30 and consequently has an inertia greatly in excess of that of the base. The body of the projectile is made of slightly-smaller diameter than the bore of the gun, so that it shall rest upon the lands or spaces between the 35 rifle-grooves, while the base or sabot is made of larger diameter or is formed with exterior ribs of any known pattern, so that it shall engage the rifle-grooves. When the proj- 40 ectile, with the base partly unscrewed, is placed in the rifled bore of the fire-arm and fired, the inertia of the body of the projectile causes it to resist the rotative tendency of the rifling, while the base being engaged by the rifles is rotated, and consequently is 45 screwed up to the body portion, so that before the projectile leaves the gun the base has been fully screwed up and its rotation is communicated to the body of the projectile. The friction of the screw-threads, increased by 50 the propulsive pressure transmitted to the body portion through the base, imparts a con-

tinuous rotative tendency to the body portion, which gradually becomes effective in rotating the body portion as it overcomes the inertia thereof, so that the body of the projectile during its travel through the bore of the gun receives an accelerating rotary motion, which with the best proportions should nearly equal the speed of rotation of the base or sabot at the instant that the latter 55 becomes screwed tightly against the body, which should occur just before the emergence of the projectile from the gun, so that at the time of passing out of the bore the base and body are rotating together at a uniform speed. 60

In a space or cavity between the partly-un- 65 screwed base and the body a mass of lubri- cating substance is placed, which by its pres- ence further resists the screwing up of the base, and serves thus to impart a rotative 70 tendency to the projectile body, and which serves the further purpose of lubricating the bore of the gun by being squeezed out there-into by reason of the screwing up of the base. As this screwing up takes place continuously 75 during the travel of the projectile through the bore, the squeezing out of the lubricant occurs also continuously, so that approxi- mately a uniform quantity of lubricant is 80 spread upon the surface of the bore during the entire travel of the projectile. The ar- 85 rangement is such that the lubricant thus ex- pelled is discharged in advance of the base or sabot, and consequently enters between the latter and the rifle grooves and lands, so that the lubricant is applied at the exact time and 90 place that it is needed, and each projectile lubricates the bore for itself instead of for the succeeding projectile.

I have shown in the accompanying draw- 90 ings several different embodiments of my in- vention.

Figure 1 is a side elevation of a shell em- 95 bodying my invention. Fig. 2 is a longitudi- nal mid-section thereof. Fig. 3 is an end ele- vation thereof. Fig. 4 is a front elevation of the screw-base removed. Fig. 5 is a frag- 100 mentary longitudinal section showing the base screwed up. Fig. 6 is a fragmentary eleva- tion, partly in mid-section, showing a slightly- modified construction of the screw-base. Figs. 7 and 8 show a modified construction designed

more especially for small-arms, Fig. 7 being a longitudinal mid-section of the projectile with its parts assembled, and Fig. 8 being an elevation showing the parts separated. Figs. 9, 10, and 11 show another construction applicable to either large or small arms, Fig. 9 being a side elevation, Fig. 10 a longitudinal mid-section, and Fig. 11 an elevation of the screw-base removed. Figs. 12, 13, and 14 are elevations, partly in longitudinal mid-section, of different constructions of the screw-base or sabot.

Referring to the drawings, let A designate the body of the projectile, and B the screw-base or sabot. The body A comprises by far the greater portion of the weight of the entire projectile. The base B is united to the body A through the medium of male and female screw-threads *a*, the sabot being normally partly unscrewed and the intervening space thus formed being filled with lubricating material. (Designated at C and C'). The projectile body A is made of such small diameter that it is not engaged by the rifle-grooves, but rests upon the intervening lands. The base B is made of somewhat larger diameter, so that it enters the grooves, or is formed with ridges or projections which take the grooves. The base or exterior portion thereof which takes the rifle grooves is constructed by preference of soft metal.

Having thus in general described my invention without special reference to any one of the constructions shown, I will now proceed to describe more particularly the several different constructions illustrated in the accompanying drawings.

Figs. 1 to 5, inclusive, illustrate a shell designed for purposes of penetration. The rear portion of the projectile body A is formed with a neck or tail *b*, having male screw-threads *a a* cut upon its exterior. The base B is formed as a screw-cap having interior or female screw-threads adapted to screw upon this neck. The screw-threads should be of somewhat steep pitch, a double thread being preferably used. When the base is partly screwed on, two cavities or spaces are formed which are filled with lubricant, the one being the space within the cup against the end of the screw-threaded neck *b*, and the other the annular space or groove around the exterior of the neck *b* and between the front edge or flange of the cup and the shoulder formed by the contraction of the neck. The latter of these spaces is filled with a mass of lubricant lettered C, while the former is filled with lubricant lettered C'. The lubricant may be tallow or any kind of grease, wax, or a mixture of tallow or wax with graphite, or it may consist of some absorbent material saturated with oil. The lubricant at C is preferably a mixture of tallow and graphite, or an absorbent—such as felt—saturated with oil, while that in the space C' may be a mixture of tallow and graphite or any suitable grease or wax alone. As the base B is screwed up

by the action of the rifle-grooves in firing, the lubricant is squeezed out, that at C being delivered to the bore of the gun just in front of the projecting portion or luting *c* of the base, which is preferably made of soft metal to enter the rifles, while the lubricant C' is squeezed out through holes or openings *d d*. The base B is preferably constructed of hard metal, in which the screw-thread is formed, and its outer or projecting portion *c* is a luting of soft metal applied to it in any suitable manner—as, for example, in the manner shown in Fig. 2—where the tubular luting of soft metal comes against a shoulder near the front of the cup-shaped base. The soft-metal luting preferably projects beyond the rear face of the head B in order to form a cup-packing to be expanded into the grooves by the gaseous pressure in firing on the principle of the expanding sabot of the Parrott shell. This construction of the base B, however, may be greatly varied, one example of which is shown in Fig. 6, where the entire base is formed of one piece of suitable metal screwing directly on the neck *b*, and formed with holes *d d* for the discharge of the lubricant. The lubricant, instead of being provided both at C and C', may be omitted in either one of these places. In Fig. 6 the lubricant is shown applied only at C'.

My invention is adapted not only to explosive shells and solid shot for ordnance, but also to bullets for small-arms.

Figs. 7 and 8 show a construction applicable to either large or small projectiles. The body A is formed with a screw-neck *b*, which is somewhat prolonged, and on which are screwed one or more nuts, two nuts B and B' being shown. A lubricating-washer C is shown as interposed between these two nuts, and another washer C² between the nut B' and the shoulder at the front of the screw-threaded neck.

The forward nut B' may be of the same diameter as the body A, so that it will not take the rifle-grooves; but the rear nut B is provided with an exterior luting of soft metal *c*, whereby it is constituted the screw-base or sabot before referred to, there being, however, this difference between this base and that shown in the preceding figures, that it is not in the form of a cup since the screw-neck *b* projects entirely through it. The washers C C² are preferably loose felt saturated with oil or impregnated with grease or wax. When the projectile is fired, the base B is first screwed up by the rifling, thereby forcing out the lubricant C, after which the nut B' is screwed up, forcing out the lubricant C². If additional nuts are used, they will be screwed up successively.

Figs. 9, 10, and 11 show another construction wherein the female screw is formed in the body A and the male screw is applied to the base B. This base is formed with a screw neck or shank *b'*, the male threads *a* on which engage female threads *a'* in a tapped hole in the rear of the projectile body A. The soft

luting *c* is preferably a cup-shaped piece of copper forced over the base *B*. The lubricant is a mass of tallow and graphite, or a washer of oiled felt arranged at *C*.

5 Figs. 12, 13, and 14 show different constructions of the base *B* in respect of the soft-metal sabot-luting *c*. In Fig. 12 this luting is shown cupped and of the same diameter as the head of the base *B*, being designed to be of the 10 same diameter as the projectile body *A*, so that it shall not enter the rifle-grooves, until expanded thereinto by the internal pressure of the gases, after the manner of the sabot of the Parrott shell. Such construction is well 15 adapted for muzzle-loading guns. In Fig. 13 the soft metal *c* is confined between two flanges or shoulders *h* and *i*, while in Fig. 14 it rests against a flange *i* at the front, and is formed with a rabbet which conceals this 20 flange.

My invention, by a simple and inexpensive construction of the projectile, realizes the important practical advantage of imparting to the projectile an accelerating rotation without resorting to the expedient of rifling the bore of the gun with an increasing or "gain" twist. My projectile is designed to be fired in barrels having a rifling of uniform twist. The disadvantage of such rifling heretofore 25 has been that the inertia of the projectile usually causes it to resist at starting the rotative movement which the twist imparts, so that until this inertia is overcome it is being forced forwardly through the bore with a 30 slower rotative movement than that corresponding with the pitch of the rifling, so that in this case the metal of the projectile is torn off by being forced across the rifle-levels, thereby injuring both the projectile and the 35 gun. To overcome this obvious difficulty, the employment of an increasing or gain twist has been resorted to, but with no very satisfactory results, such a twist being found to have the disadvantages that it tends to rotate 40 the front of the projectile at a more rapid speed than the rear portion thereof and that it twists and distorts the projectile in such way that it materially increases the friction in its passage through the bore. These difficulties have increased with the change that 45 has taken place in the proportions of projectiles in the direction of an increase of their length in proportion to their caliber.

With my improved projectile the theoretical advantages of the increasing twist are 50 realized in the use of a gun rifled with a uniform twist, since the inertia of the projectile is overcome gradually, the screw-base being of very little weight and affording, consequently, very slight inertia, being caused to partake immediately of the rotary motion due to the pitch of the rifling, and this motion being gradually communicated to the projectile body. By the use of my invention a rifling 55 of more rapid twist can be employed than has been hitherto practicable. This constitutes an important desideratum, in view of the

present tendency toward the reduction of the caliber and the necessary increase of the length of the projectile, it being well known 70 that the greater the length of a projectile in proportion to its caliber the more rapid revolution it requires to cause it to fly end on.

My invention also possesses very important advantages in the thorough and effective 75 lubrication of the barrel, whereby the injury of the projectile in being fired is prevented and the undue heating of the barrel and the cutting of the rifle grooves and lands are 80 avoided.

The portion of my invention which relates to the lubrication may be omitted, while retaining the advantages inherent in the screw-base or sabot; but in such case it is preferable to substitute for the mass of lubricant 85 some other similar resisting substance or device for communicating from the base to the projectile body the rotary tendency. This rotary movement may be communicated solely by the friction of the screw-threads, 90 but it is preferable to make the screw-threads as nearly frictionless as possible and to substitute some sufficiently-resisting material or element for thus communicating the rotation.

I claim as my invention the following-defined novel features and combinations, substantially as hereinbefore specified, namely:

1. A projectile having a separate base or sabot connected to it through the medium of a screw-thread and normally partly unscrewed, 100 said base being adapted to engage the rifle-grooves in firing and to be rotated thereby, and by reason of such rotation and the inertia of the body of the projectile to be screwed up to the latter. 105

2. A projectile having a separate base or sabot connected to it through the medium of a screw-thread and normally partly unscrewed, and with a partially-resisting substance or filling between a shoulder or face 110 on the front of said base, and a shoulder or face at the rear of the body of the projectile adapted to partially resist the screwing up of the base in the operation of firing, and by such resistance to communicate the rotary movement of the base gradually to the body of the projectile in order to gradually overcome the inertia of the latter and impart to it an accelerating rotation. 115

3. A projectile having a separate base or 120 sabot connected to it through the medium of a screw-thread and normally partly unscrewed, and provided with a lubricating substance between said base and the body of the projectile adapted to be gradually 125 squeezed out by the screwing up of the base during the operation of firing.

4. A projectile consisting of a body portion and a separate base or sabot, the one formed with a screw-threaded neck and the other 130 with a screw-threaded socket engaging said neck, a cavity formed within the socket and provided with holes extending from said cavity to the exterior, combined with a filling of

lubricating substance in said cavity, whereby it is adapted to be squeezed out through said holes by the screwing up of the base against the body portion of the projectile, and means 5 for operating said base.

5. A projectile having its body portion formed with a contracted screw-threaded neck at its rear, and a separate base formed with internal screw-threads screwing upon said neck, normally partly unscrewed, and formed 10 to project beyond the diameter of the body

in order to engage the rifle-grooves, whereby it is adapted to be screwed up to the body during the operation of firing.

In witness whereof I have hereunto signed 15 my name in the presence of two subscribing witnesses.

SELDEN A. DAY.
